UNITED STATES PATENT OFFICE.

ANTHONY ISKE AND ALBERT ISKE, OF LANCASTER, PENNSYLVANIA.

MOTOR.

SPECIFICATION forming part of Letters Patent No. 253,868, dated February 21, 1882.

Application filed November 4, 1881. (No model.)

To all whom it may concern:

Be it known that we, ANTHONY ISKE and ALBERT ISKE, citizens of the United States of America, residing at Lancaster, in the county 5 of Lancaster and State of Pennsylvania, have invented certain new and useful Improvements in Motors; and we do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 This invention relates to motors which operate by the shifting of inclosed volatile liquid *in vacuo* from one chamber to another and higher chamber under the influence of heat and its own gaseous pressure and by the gravity of the liquid thus shifted or transferred. Letters Patent No. 242,454, granted to us on the 7th of June, 1881, broadly cover motors operating on this principle; but in said patent and in Letters Patent No. 243,909, granted to us July 5, 1881, the only forms of motor shown and described operate by rotary motion. In a subsequent application by Albert Iske, one of the undersigned, an oscillating motor is shown embodying the same principle. The present 30 application embodies a further improvement in the same line, which improvement consists in the combination of an oscillating tube having at each end a receptacle for volatile liquid with a calorific chamber or chambers into which these receptacles dip alternately.

35 The invention further consists in providing each end of said tube with a cover which extends over the receptacle at that end and which closes that side of the calorific chamber as said 40 receptacle descends into it, thereby preventing waste of heat.

The invention further consists in providing the calorific chamber with a gate or analogous device and connecting the same with the oscillating tube aforesaid in such manner that the descent of either receptacle causes said gate to cut off the hot air entirely from the other receptacle and give the full effect of the current to the descending one.

50 The invention consists, finally, in certain pe-

culiarities of combination and construction of the devices hereinafter set forth.

In the accompanying drawings, Figure 1 represents a rear perspective view of our improved motor embodying the present invention. Fig. 55 2 represents a vertical section of the same, taken longitudinally through the axial line of the tube. Fig. 3 represents a front elevation, showing the pump-operating mechanism.

The same letters of reference designate the 60 same parts in all of the above figures.

A designates a hollow casing, preferably of metal, which constitutes the supporting-frame for the motor and also incloses the calorific chamber. This casing is open at the bottom 65 and also at each of its upper corners, these upper openings forming entrances *a a'* for each of the receptacles hereinafter described. In the front of said casing, at the bottom thereof, is a door, *A'*, for the insertion and removal of 70 a lamp, *B*, or other calorific device. A V-shaped partition, *A²*, converging downward from the top of the casing toward the lamp, divides the calorific chamber into two diverging 75 passages or apartments, one extending from the lamp to entrance *a* and the other to entrance *a'*. On the top of said casing are two standards, *C C*, which afford bearings for trunnions *c c'*, that are formed with a sleeve, *D*, rigidly secured on the middle part of a tube, *E*. 80 This tube is of sheet metal or other stiff material, and has at its ends cylindrical receptacles *E' E'*. The said tube and receptacles are exhausted of air and supplied with some easily-vaporizable liquid—for instance, alcohol—85 in sufficient quantities to partly fill the same. Each end of the said tube is also provided with a flanged cap, *F*, which extends over the adjacent receptacle and is adapted to fit about 90 the entrance in the casing which receives said receptacle. Thus, when receptacle *E'* descends into entrance *a*, as shown in dotted lines in Fig. 1, its cap *F* entirely closes this entrance. The heat is thus prevented from escaping, and also is reflected upon the top of said receptacle. 95

The trunnion *c*, before referred to, carries in front of its standard *C* a gear-wheel, *G*, which meshes with two racks, *H H*, formed on the upper ends of piston-rods *I I*, which operate in pump- 100

cylinders J J, supported on a ledge, j, attached to the front of casing A. Of course any other form of mechanism may be operated instead of these pumps by said cog-wheel and pinion or by cranks or other suitable devices. 5 The other trunnion, e', (which, if desired, may be in one piece with trunnion e, forming a continuous shaft,) carries a crank-arm, k, which is connected by a long rod or pitman K to a 10 crank-arm, l, on a rock-shaft, L, journaled in the front and rear walls of said casing A. This rock-shaft carries a depending gate, M, which vibrates from side to side as the tube E oscillates on its trunnions or transverse shaft. 15 The operation of the machine is as follows: When receptacle E is within the calorific chamber and receptacle E² at its highest point the gate M is in position to direct the entire body of heated air against the former receptacle. 20 The liquid in this receptacle becomes partly vaporized; but as the end of the tube E is extended nearly through this receptacle the vaporized liquid is obliged to drive by expansion the remainder of the liquid before it through 25 said tube in order to find room. This results in transferring bodily and almost instantly the whole supply of fluid from the lower receptacle to the upper one. The latter then preponderates, and therefore descends to become the 30 lower in its turn. During this descent the trunnion-cranks and connecting-rod or pitman above described cause shaft L to rock in the opposite direction, so that the gate M cuts off the hot air from entrance a and allows it to 35 flow to entrance a'. Receptacle E² then passes within or through said entrance containing the alcohol, again liquefied by descending through the air. The heated liquid then turns partly to vapor again, and the portion that remains 40 fluid is once more forced by the expansion of that vapor through the tube to receptacle E' again. In this way a very rapid oscillating motion may be obtained. The expansion of the ends of the tube nearly through the receptacles attached thereto will be found fully de- 45

scribed in the second of our earlier patents hereinbefore referred to.

Of course other forms of cut-off mechanism may be substituted for the gate above described and its operating shaft-cranks and pitman. 50 It is, however, a very convenient and satisfactory device for the purpose designed. Hot water may be substituted for hot air as a means of partial vaporization.

Of course the receptacles may be duplicated, 55 or the tube, or both.

Having thus fully described our invention, what we claim as new, and desire to secure by Letters Patent, is—

1. An oscillating tube having at each end a 60 receptacle for volatile liquids and a cover, in combination with a calorific chamber provided with an entrance for the admission of said receptacles, each entrance being adapted to be closed by the appropriate cover after the receptacle has entered.

2. In combination with an oscillating tube and a pair of receptacles for volatile liquid, attached to the ends of said tube, a calorific chamber divided into two parts or passages, 70 and a gate or valve within said chamber connected to said tube in such manner that the oscillation of said tube cuts off the hot air from one of said parts or passages and directs it into the other.

3. In combination with tube E and terminal receptacles E' E², the casing A, the gudgeons or pivot-shaft for said tube, rock-shaft L, gate M, and the cranks and pitman or connecting-rod, whereby the oscillation of said tube is 75 enabled to automatically control the vibration of said gate, substantially as set forth.

In testimony whereof we affix our signatures in presence of two witnesses.

ANTHONY ISKE.
ALBERT ISKE.
